CLAIM

The ornamental design for an air conditioner switch panel for an automobile, as shown and described herein.

DESCRIPTION

FIG. 1 is a left side perspective view of an air conditioner switch panel for an automobile;

FIG. 2 is a right side perspective view thereof;

FIG. 3 is a front view thereof;

FIG. 4 is a top plan view thereof;

FIG. 5 is a left side view thereof; and,

FIG. 6 is a right side view thereof.

The broken lines in the drawings illustrate portions of the air conditioner switch panel for an automobile that form no part of the claimed design.
